United States Patent Office

Des. 224,170
Patented July 4, 1972

224,170

MUFFLER

Douglas Gordon, Hartford, Wis., assignor to Briggs & Stratton Corporation, Milwaukee, Wis.

Filed Apr. 19, 1971, Ser. No. 135,532

Term of patent 14 years

Int. Cl. D15—01

U.S. Cl. D77—1

FIG. 1.

FIG. 2.

FIG.3.

FIG.4.

FIG. 1 is a front view of a muffler embodying my new design;

FIG. 2 is a side view thereof;

FIG. 3 is a rear view thereof; and

FIG. 4 is an end view of the muffler.

I claim:

The ornamental design for a muffler, as shown.
